UNITED STATES PATENT OFFICE.

ALFRED C. EINSTEIN, OF ST. LOUIS, MISSOURI.

LIGHTING-FIXTURE.

1,161,118.

Specification of Letters Patent. Patented Nov. 23, 1915.

Application filed September 8, 1914. Serial No. 860,738.

To all whom it may concern:

- Be it known that I, ALFRED C. EINSTEIN, a citizen of the United States, residing at St. Louis, Missouri, have invented a certain 5 new and useful Improvement in Lighting-Fixtures, of which the following is a full, clear, and exact description, such as will enable others skilled in the art to which it appertains to make and use the same.
- 10 This invention relates to lighting fixtures of the type which comprise a reflector and a shield arranged above and below the lighting unit, respectively, so as to produce an indirect light.
- 15 One object of my invention is to provide a neat and ornamental lighting fixture of the character mentioned that can be manufactured at a low cost and which comprises only a few parts of simple construction that 20 can be easily assembled by an unskilled person.

Another object is to provide an indirect lighting fixture of the character mentioned that can be arranged some distance below 25 the ceiling instead of being placed directly against the ceiling and which is so designed that a black spot or shadow will not form on the ceiling above the top reflector of the fixture.

30 Another object is to provide an electric fixture of the character described in which the top reflector is held in position by co-operating portions on the incandescent lamp socket and on a cap member to which the 35 sustaining or supporting means of the fixture is fastened. And still another object is to provide an indirect lighting fixture in which the means that sustains or supports the fixture is connected to the top reflector at approximately the center of same and the bottom shield is in turn supported by said top reflector.

40 Other objects and desirable features of my invention will be hereinafter pointed 45 out.

Figure 1 of the drawings is an elevational view, partly in vertical section of a lighting fixture constructed in accordance 50 with my invention; Fig. 2 is a bottom plan view on a reduced scale of the fixture shown in Fig. 1; Fig. 3 is a similar view illustrating a slight modification of my invention;

and Fig. 4 is a perspective view illustrating a slight modification.

I have herein illustrated my invention 55 embodied in an electric-light fixture, but it will, of course, be understood that any other suitable type of light could be used without departing from the spirit of my invention, for the particular lighting unit used in connection with the fixture is immaterial so far 60 as my broad idea is concerned.

Referring to the drawings which illustrate the preferred form of my invention, A designates a lighting unit, herein shown 65 as an incandescent lamp, B designates a reflector that is arranged above said lighting unit, and C designates a shield arranged below said lighting unit so as to cause the rays of light to be refracted onto the reflector B. The reflector B is formed from material that is transparent or translucent so that some of the light from the lighting unit A will penetrate through said reflector and thus produce an indirect light on the 70 ceiling directly above the reflector, the term 75 "transparent" being herein used to mean a substance or member that is perfectly transparent or only partly so, as translucent. The under side of the reflector B is preferably 80 provided with a brilliant reflecting surface so that some of the light from the lighting unit which strikes the underside of the reflector B will be reflected downwardly. The shield C, which is arranged under the lighting unit A, can either be formed of opaque 85 material or transparent or translucent material, it being preferable to form the shield C from translucent material so as to produce an opalescent effect.

90 In the preferred form of my invention as herein shown the top reflector B is disk-shaped and is formed from fragile material that has a metallic reinforcing and strengthening means permanently embedded in same, 95 the peripheral edge of the reflector being provided with a metal binding 1. I prefer to form said reflector from a sheet of wire glass, namely, glass in which a wire mesh is embedded so as to reinforce and 100 strengthen the glass, and the upper surface of the glass that constitutes the top surface of the reflector B is preferably ground so as to tend to prevent the rays of light

- from penetrating through same, thereby causing the majority of the rays to be reflected downwardly. The under side of said reflector may either be plain or corrugated. As shown in Fig. 2, the reflector B is provided on its under side with radial corrugations 2 that tend to spread the light over a relatively large area or, in other words, reflect the rays outwardly, but, if desired, the reflector B may be provided on its under side with concentric corrugations 3, as shown in Fig. 3, so as to concentrate the rays of light and confine them to a relatively small area.
- The supporting or sustaining means of the fixture may consist of one or more rods or chains D that depend from the ceiling and which are preferably connected to the top reflector B at approximately the center of same, as shown in Fig. 1, and the bottom shield C is in turn suspended from or supported by the top reflector B. The top reflector B may be connected in various ways to the means that sustains same but in the preferred form of my invention as herein shown said top reflector is securely clamped between coöperating flanges 4 and 5 on the lamp-socket 4^a and on a cap member 5^a, said lamp-socket passing through an opening at the center of the reflector B and being screwed into the cap member 5^a, as shown in Fig. 1. A washer 6 of some suitable soft or non-metallic material, is preferably interposed between the under side of the reflector B and the flange 4 of the lamp-socket, and the cap member 5^a is provided with an eye or ring 7 to which the sustaining means D is secured. The shield C that is arranged under the lighting unit, is suspended from the top reflector B preferably by means of chains 8 that engage hooks 9 on the upper edge of the shield C and hooks 10 formed on the lower ends of bolts 11 which pass through the reflector B, as shown in Fig. 1.
- By forming the top reflector B from wire glass and grinding the top surface of the same I obtain, at a low cost, a translucent reflector that has a brilliant reflecting surface. Furthermore, said reflector is exceptionally strong and rigid, thereby enabling the reflector to be supported from its center and the bottom shield to be suspended from the reflector. In other words, the top reflector has sufficient strength and rigidity to carry the bottom shield, and the means that sustains said top reflector can be connected to the center of same instead of to the edge portions of the top reflector, thereby enabling the top reflector to be arranged some distance below the ceiling instead of directly against the ceiling. In view of the fact that the peripheral edge portion of the top reflector is free from upwardly projecting portions or flanges that would obstruct the rays of light, there is no liability of a black spot or shadow forming on the ceiling above the reflector. By clamping the top reflector in position between cooperating flanges or portions on two members, such, for example, as the lamp-socket and the cap member to which the sustaining means is fastened I overcome the necessity of drilling holes in the reflector and using separate fastening devices for securing it in position. And another advantage of such a construction is that it can be assembled easily by an unskilled person, thereby enabling the fixture to be shipped in knock-down form from the manufacturer to the user who can install the fixture without the aid of a skilled mechanic.
- The fixture presents a neat and ornamental appearance, it produces an indirect light without liability of a shadow or black spot forming on the ceiling directly above the reflector, and it can be made in very large sizes owing to the strength and rigidity of the top reflector.
- If desired, the socket 4^a can be provided with radially projecting arms 4^b, as shown in Fig. 4, that lie underneath the reflector B and thus take the strain off the center portion of said reflector which is clamped by the flanges on said socket and on the cap member 5^a.
- While I prefer to arrange the reflector B some distance below the ceiling and connect the sustaining means D of the fixture to the cap member 5^a it will, of course, be understood that the top reflector could be arranged and sustained in various other ways without departing from the spirit of my invention.
- Having thus described my invention, what I claim as new and desire to secure by Letters Patent is:
1. A lighting fixture comprising a flat, transparent top reflector arranged some distance below the ceiling and having its peripheral edge portion free from upwardly-projecting portions that would tend to prevent the rays that pass upwardly through same from spreading out laterally over the ceiling, and a translucent diffusing shield of less diameter than said top reflector arranged under the lighting unit.
  2. A top reflector for lighting fixtures consisting of a flat, horizontally-disposed transparent member arranged some distance below the ceiling and having its peripheral edge portion free from any upwardly-projecting flanges or other portions that would tend to prevent the rays which pass upwardly through same from spreading out over the ceiling, the underside of said member being corrugated.
  3. A top reflector for lighting fixtures consisting of a flat, horizontally-disposed transparent member arranged some distance below the ceiling and having its peripheral

edge portion free from any upwardly-projecting flanges on other portions that would tend to prevent the rays which pass upwardly through same from spreading out 5 over the ceiling, the underside of said member being corrugated and the upper side of said member being ground.

4. A lighting fixture comprising a flat top reflector formed from a sheet of glass 10 whose underside is corrugated and whose

upper side is ground, and a translucent diffusing shield of less diameter than said top reflector arranged under the lighting unit.

In testimony whereof I hereunto affix my signature in the presence of two witnesses, 15 this third day of September 1914.

ALFRED C. EINSTEIN.
